UNITED STATES PATENT OFFICE.

JAMES CARROTHERS, OF PAVONIA, OHIO.

ROTARY CULTIVATOR.

SPECIFICATION forming part of Letters Patent No. 499,211, dated June 13, 1893.

Application filed January 23, 1893. Serial No. 459,320. (No model.)

To all whom it may concern:

Be it known that I, JAMES CARROTHERS, a citizen of the United States, residing at Pavonia, in the county of Richland and State of Ohio, have invented a new and useful Harrow, of which the following is a specification.

This invention relates to harrows; and it has for its object to provide certain improvements in machines of this character, whereby the ground shall be thoroughly and effectually broken, preparatory to planting, and to this end the invention primarily contemplates a machine having special arrangements of harrowing-teeth in combination with certain adjustments to secure the best possible results.

With these and other objects in view which fall within the scope of the invention, the same consists in the novel construction, combination and arrangement of parts hereinabove more fully described, illustrated and claimed.

In the accompanying drawings, Figure 1 is a top plan view of a harrow constructed in accordance with this invention. Fig. 2 is a side elevation of the same. Fig. 3 is a vertical longitudinal section view thereof. Fig. 4 is an enlarged detail in perspective of one end of the vertically adjustable harrow shoe-frame.

Referring to the accompanying drawings:— A represents the axle having at the opposite ends thereof the spindles *a*, upon which are journaled the opposite supporting and drive wheels, *B*, carrying the machine and providing means for transmitting motion to one part thereof as will be hereinafter more fully described.

Fixedly secured to the top side of the axle *A*, is the seat frame *C*, extending to the front and rear of the axle and having the opposite longitudinal frame bars *c*, to which at *c'*, is securely bolted the rear end of the under harrow supporting frame *D*. The said harrow supporting frame *D*, comprises the opposite frame bars *d*, suitably connected by ordinary cross-bars, and said frame extends from its point of connection in rear of the axle to the upper seat-frame, beneath the axle and to the front of the same.

To the extended front ends of the opposite bars *d*, of the under frame are secured the front parallel supporting bars *E*, to the inner

of which, the extreme front ends of the opposite frame bars *c*, of the seat-frame are bolted. The parallel supporting bars *E*, in front of 55 the wheels *B*, extend beyond the opposite sides of the frames between the wheels and to a point beyond the wheels as clearly illustrated in Fig. 1 of the drawings, and are connected at such ends by the horizontal end frame-bars 60 *F*. The opposite end frame bars *F*, support at each end thereof the opposite curved hanger feet *G*, which feet are provided with longitudinally disposed slots *g*, to receive the combined guide and supporting pins *H*. The 65 said pins *H*, are round in cross-section so that the same can freely move in the slots *g*, and are secured to each end of the curved shoe bars *I*, which are thus mounted to move vertically, and being curved similar to ordinary 70 runners are adapted to freely slide over obstructions, which are above the ordinary level, and thus relieve the entire machine from strain, said shoe-bars being adapted to be simultaneously and independently adjustable 75 by the means hereinafter described.

Mounted upon the shoes *I*, supported beyond the wheels *B*, and near their front ends, are the bearing-boxes *J*, which receive the journal ends of the harrow roller *K*. The said 80 harrow-roller *K* is provided with alternate rows of roller or harrow teeth *k*, which are designed to pierce the clod and harrow the earth as the machine travels over the ground. As will be understood by those skilled in the 85 art, the teeth of the roller, when the machine is in operation, walk over the surface of the ground, and therefore the said roller receives its movement from the forward motion of the machine under ordinary circumstances, but 90 in order to break up extra hard surfaces or clods, supplemental means are provided for rotating the roller. To provide for this auxiliary, the roller *K*, is provided with an intermediate sprocket *L*, which receives one end 95 of the endless chain *l*, the other end of which passes over the sprocket wheel *l'* loosely mounted on the transverse shaft *P*. The said transverse shaft *P*, is journaled below and in rear of the axle on the under supporting frame *D*, 100 and carries at opposite ends thereof the pinions *M*, meshing with the internal gear wheels or rings *m*, removably secured to the spokes of the opposite wheels *B*, to transmit motion

to said transverse shaft. The sprocket wheel on the transverse shaft is provided with a clutch face m' , which when it is desired to communicate motion to the roller chain l , is 5 engaged by the sliding clutch sleeve m^2 , mounted to slide on the shaft l^2 adjacent to the loose sprocket wheel, and is controlled by an ordinary foot lever m^3 , mounted upon one of the side bars d , and arranged adjacent 10 to the operator, to be used for the purposes specified.

Secured at their ends to the opposite shoes I, and connecting the same in rear of the harrow roller K, are the parallel tooth bars N. 15 Fixedly secured at one end to the front tooth bar nearest the roller K, are a transverse series of cleaning fingers n , projecting forwardly from the tooth bars, to which the same are secured, to a point near the roller K, and are 20 so arranged as to travel between the teeth on the harrow roller, to relieve the same from clogs or other impediments clinging thereto. The front tooth bar M, also carries the perpendicular or straight unyielding harrow 25 teeth O, of ordinary construction and adapted to have their upper bolt ends secured to the tooth bar in the ordinary manner, and said straight harrow teeth are arranged in rear of the roller K, so as to pierce the surface of the 30 ground in the spaces left between the teeth of said roller and thereby provide extra means for thoroughly breaking the ground.

In order to complete the harrowing devices carried by the movable shoes I, I employ a 35 series of rearwardly extending curved spring harrow teeth P. The spring harrow teeth P, are secured at one end to every alternate perpendicular tooth P, on top of the front tooth-bar, and extend from such point of connection 40 over the top of the rear tooth-bar N, to which they are also bolted as at p, and have their curved spring ends curved below the tooth bar, to engage the surface of the ground and thereby complete a combination of roller, 45 straight unyielding, and spring harrow teeth, to secure the complete and effectual breaking of the ground, all of said harrowing devices being vertically adjustable with the end shoes I, by the means to be presently described. 50 The opposite hangers G, are braced in their position by the diagonal brace-rods g' , in order to strengthen the same for the support and guiding of the opposite shoes, to which are centrally secured at their lower ends the 55 lifting rack bars Q, provided along one edge from their upper ends with the teeth q. Said rack bars are held steady in their upward movement by suitable guide clips q' , secured to the opposite end bars F. The rack bars Q, 60 are engaged by the toothed segments R, secured to the outer ends of the opposite independent rock shafts r. The said opposite rock shafts r, are journaled at their outer ends in the end bars F, and at their inner ends 65 to the under sides of the front ends of the seat frame bars c, and each of said shafts is provided with a crank arm r' , to which crank

arms are connected one end of the opposite operating wires S, the other ends of which are connected to the raising and lowering levers s. 70 The said levers s, are pivoted at their lower ends to the opposite frame bars c, and are provided with the usual dogs s', engaging the adjacent segments s^2 , which provide means for holding the levers at any adjusted position. The levers s, are arranged in front of the longitudinally adjustable seat T, supported upon the rear end of the seat frame C over the ordinary tool box t, so that either or both of the levers are under the control of 80 the driver at one time. From the adjustments just described, it will now be understood more clearly, that one end of the harrow can be raised independently of the other end in order to clear an obstruction at that 85 particular end, and it will also be apparent that by operating both levers, the entire harrow can be lifted above and out of contact with the ground when the same is not in use.

Pivots secured at its inner end to the inner of the parallel supporting bars E, as at U, is the forwardly extending tongue or draft beam u, to which the team is attached in taking the harrow over the field, to be broken, and said draft beam or tongue u is designed 95 to work loosely in the clevis or clip V, when the harrow is in operation, in order to allow the same a vertical play when traveling over uneven surfaces. The clevis V, is secured to the front bar E to secure the result noted, 100 and is sufficiently large to allow for the movement necessary, but when the entire harrow is lifted from the ground, in order to prevent the same from scratching the road or the ground over which the same is being transported, I employ the securing pin v, adapted to pass transversely through perforations in the clevis above the tongue, to hold the harrow frame firmly thereto. Now, from the construction herein described, it will be observed, that, 105 the opposite ends of the harrow project beyond the wheels, so that the wheels travel always over harrowed ground and therefore are not likely to raise the harrow teeth out of the ground by passing over uneven surfaces, 110 which is an important point in harrowing land. It may be further observed at this point, that the distance between the traveling wheels B, is designed to be the same as the distance between the rows of corn to be 115 planted, so that as the machine moves over the ground, the same acts in the capacity of a marker to evenly mark off the land, and in order to insure the equal marking of the land, I employ a side marker guide W, pivotally secured at w, to a front corner of the harrow frame and adapted to travel in the last path left by the wheel so that the machine is 120 guided straight for marking purposes. It may be additionally noted at this point, that in order to hold the sprocket chain l, which communicates movement to the harrow roller, sufficiently tight, I employ an intermediate 125 tightener pulley X, supported below the un-

der frame D, and contacting with the upper portion of said chain as fully illustrated in the drawings.

It is thought that the construction and operation and many advantages of the herein described adjustable harrow will now be apparent to those skilled in the art.

Having thus described my invention, what I desire to secure by Letters Patent is—

- 5 1. In a harrow, the combination with the wheel frame; of a front supporting frame having the opposite end bars, slotted hanger feet depending from the extremities of each of said end bars, vertically adjustable curved shoes having their extremities loosely engaging the slots of said hangers, harrowing devices connecting the opposite shoes, and means for adjusting said shoes, substantially as set forth.
- 10 2. In a harrow, the wheel frame, a transverse supporting frame in front of the wheel frame, longitudinally slotted hangers depending from opposite side extremities of said transverse supporting frame, separate shoes having pins at their extremities which freely engage the slots of said depending hangers, a toothed harrow roller journaled on the opposite shoes, separate straight and spring harrow teeth supported in position between and adjusted with said shoes, and means for simultaneously or independently adjusting the opposite shoes, substantially as set forth.
- 15 3. In a harrow, a wheel supported frame, a transverse supporting frame mounted on the front end of the wheel frame, curved slotted hangers arranged at opposite ends of the transverse supporting frame, curved shoes having guide and supporting pins at each end working in the slots in said hangers, harrowing devices connecting the opposite shoes, and means for simultaneously or independently adjusting the opposite shoes, substantially as set forth.
- 20 4. The combination in a harrow of the wheel supported frame, a transverse supporting frame at one end of the wheel frame and

having opposite depending hangers, a vertically adjustable tooth frame mounted in said hangers, rack bars secured to opposite ends of the tooth frame and extending upwardly therefrom, opposite independent rock shafts mounted in the supporting and wheel frames and having at their outer ends toothed segments engaging said rack bars, and crank arms at their inner ends, and operating levers connected with said crank arms, substantially as set forth.

50 5. In a harrow, the wheel frame, a transverse supporting frame mounted at the front end of the wheel frame and having depending hangers, opposite adjustable shoes mounted in said hangers, a toothed harrow roller journaled on the opposite shoes and moving with the machine, and auxiliary means for driving the roller, substantially as set forth.

55 6. In a harrow, the combination with the supporting frames, of the opposite vertically adjustable shoes, a toothed harrow roller mounted on and near the front ends of said shoes, parallel tooth bars connecting the opposite shoes in rear of the roller, and harrow teeth secured to said tooth bars, substantially as set forth.

60 7. In a wheel harrow, the combination of opposite vertically adjustable shoes, a harrow roller mounted on said shoes, auxiliary means for driving said roller, parallel tooth bars connecting the shoes in rear of the roller, a series of transverse cleaning fingers secured to one of the tooth bars near the roller, straight harrow teeth secured to the bar nearest the roller, and spring harrow teeth secured to the top of both tooth bars, and curving over the top of the rear tooth bars, substantially as set forth.

75 8. In testimony that I claim the foregoing as my own I have hereto affixed my signature in the presence of two witnesses.

JAMES CARROTHERS.
